CLAIM

The ornamental design for a lidar, as shown and described.

DESCRIPTION

FIG. 1 is a front perspective view of a lidar in accordance with the present disclosure;

FIG. 2 is a rear perspective view of the lidar shown in FIG. 1;

FIG. 3 is a view of the lidar shown in FIG. 1 from the front; FIG. 4 is a view of the lidar shown in FIG. 1 from the rear; FIG. 5 is a view of the lidar shown in FIG. 1 from the left; FIG. 6 is a view of the lidar shown in FIG. 1 from the right; FIG. 7 is a view of the lidar shown in FIG. 1 from the top; and,

FIG. 8 is a view of the lidar shown in FIG. 1 from the bottom.

The broken lines in the figures show portions of the lidar that form no part of the claimed design.
